DEXTER STEVENS, OF ESMOND, RHODE ISLAND, ASSIGNOR TO THE ESMOND MILLS,
OF ESMOND, RHODE ISLAND, A CORPORATION OF RHODE ISLAND

CONVERTIBLE BLANKET

Application filed May 10, 1928. Serial No. 276,671.

This invention pertains to blankets and more particularly to a blanket so constructed and having such adjunctive elements that it may serve as a blanket in the usual manner or, at will, may be converted into a hammock, or arranged so as to function both as a hammock and blanket at the same time.

Usual types of fabric hammock, so far as I am aware, are made either of thin and more or less open-mesh fabric, or of canvas or similar strong but harsh and stiff material. To assure ease and comfort, particularly the proper degree of warmth, users of such hammocks are constrained to provide a blanket, pad, or the like to lay in the hammock bottom whereby to ameliorate the harshness of the hammock fabric and to prevent air from passing up through the hammock from beneath, and under many conditions of use to provide a blanket as a coverlet.

In accordance with the present invention, I provide a blanket of usual weave, consisting of any suitable textile fibre such as cotton, silk, artificial silk, etc., but preferably containing a substantial percentage of warm material, for example, wool, camel's hair, or like material, and napped to make it soft, warm, and downy. This blanket is preferably reinforced at its opposite ends, conceivably by interweaving heavy strong weft at these points, but preferably by securing bindings of strong canvas, leather or the like to the opposite ends of the blanket. I also prefer to provide the lateral edges with similar reinforcing bindings which, if desired, may be somewhat narrower than the end bindings. I also find it advisable to furnish the blanket with one or more intermediate reinforce strips on one or both sides. These binding and reinforce elements may be secured to the blanket material by one or more rows of stitches or in any other desired manner and may be designed to impart an ornamental appearance to the blanket, as for example by the use of contrasting colors.

I also provide a series of fastener elements, preferably spaced openings through the binding strips and blanket material at each end of the blanket, reinforcing the edges of the openings in any desired manner, as for

example by the use of metallic eyelets. The series of openings may extend across the entire width of the blanket or only from one edge to the central reinforce strip as may be preferred. I also provide suspension devices for each end of the blanket, such suspension devices being of a type commonly employed for suspending fabric hammocks and each comprising for example a rigid ring and a series of suspension elements (ropes, chains, or other equivalent means) diverging from the ring. Each rope or chain preferably has a loop end adapted to be passed through one of the openings at the end of the blanket and to be releasably retained therein by a suitable interlocking element, for example a piece of rope extending transversely of the blanket and which is threaded through successive loops of the suspension device. If the blanket be doubled before the loops are passed through the openings, the resulting hammock comprises a double thickness of the soft and downy blanket material to support the user, an arrangement very useful and satisfactory in the daytime or whenever the air is warm. On the other hand if the suspension loops be threaded through the openings in one half only of the blanket, the resulting hammock provides one thickness of soft warm material for supporting the user and a second thickness which may be drawn over him as a coverlet. It is also possible to pass the loops through a double thickness of blanket at one end and through a single thickness at the other, thus providing a device somewhat similar to a sleeping bag, although suspended in the manner of a hammock, in which a single ply of the blanket material supports the user while the upper or cover ply is secured at its lower end but is normally free at its upper end and at one side to permit the user to slip beneath it.

In the accompanying drawings, I have illustrated one desirable embodiment of the invention by way of example and in the drawings:

Fig. 1 is a plan view of the blanket opened out and without the suspension devices;

Fig. 2 is a plan view of the blanket doubled longitudinally and having suspension devices

at its opposite ends, the suspension devices engaging both plies of the blanket;

5 Fig. 3 is a view similar to Fig. 2 but showing the suspension devices at one end engaging the lower ply only of the blanket;

Fig. 4 is a fragmentary detail, to larger scale, of the lower left-hand corner of the device as seen in Fig. 2;

10 Fig. 5 is a section on the line 5—5 of Fig. 4;

Fig. 6 is a plan view similar to Fig. 1 but showing a modified construction;

15 Fig. 7 is a diagrammatic section on the line 7—7 of Fig. 6; and

Fig. 8 is a similar section illustrating a further modification.

Referring to the drawings, the numeral 1 indicates a blanket which may be of usual construction, consisting of interwoven warps and wefts and consisting wholly of cotton, 20 wholly of wool, or of any desired mixture of these or other textile materials. This blanket is napped and finished in accordance with usual methods to give it a soft, warm, and downy surface, and if desired the blanket may 25 be made more or less waterproof, either in weaving or by subjecting it to a waterproofing process.

30 In accordance with my present invention I preferably reinforce this blanket at its opposite ends by means of reinforce strips 2 and 3, respectively. These strips may be of any suitable material, but strong and durable, for example, canvas or duck, and these reinforce strips preferably are applied in the form of 35 bindings, covering the edges of the blanket material. The strips may be secured to the blanket in any desired manner as, for example, by means of one or more rows of stitches 4.

40 I also prefer to reinforce the lateral edges of the blanket as, for example, by applying binding strips 5 and 6, respectively, to such edges. Furthermore, for additional strength, I contemplate providing one or more reinforce strips 7 extending longitudinally of the 45 blanket, and have here shown one such strip disposed substantially at the central fold line of the blanket. The strip 7 may be applied to one side only of the blanket material or to 50 both sides as may be preferred.

55 While I have just described the various reinforce elements as consisting of strips of material applied to the completed blanket, I contemplate that similar results possibly may be obtained by interweaving suitable warps and wefts during the production of the blanket proper.

60 I provide a series of spaced openings 8 extending along each end margin of the blanket, such openings preferably passing through the reinforce strips 2 and 3, respectively. Each series of openings preferably extends from one lateral edge to the other of the blanket, although for certain purposes they need extend only from one lateral edge to the central

fold line. The edges of these openings preferably are reinforced, as for example by means of eyelets 9. The article thus provided may be used as a bed or camping blanket in the same way as any ordinary blanket, or as a sleeping bag as hereafter more fully described.

70 For cooperation with this blanket to permit it to be converted into a hammock, I provide a pair of suspension devices, each preferably 75 consisting of a rigid ring 10 of metal or the like, and a plurality of suspension elements 11, for example cords or chains, attached at one end to the ring 10 and having loops 12 at their other ends for attaching them to the 80 blanket. A convenient mode of attaching the looped end of the suspension element to the blanket is by passing the looped end through one of the eyelets 9, as shown in Fig. 5, and then threading a rope or other securing element 13 through the loop. A single short length of rope 13 may in this way be interengaged with all of the suspension elements at one end of the hammock, securely holding the suspension elements in place but permitting 85 them to be disconnected from the hammock at will merely by withdrawing the rope from the loops 12.

90 As shown in Fig. 2, the blanket is doubled along its central line 7 and the loops of the 95 suspension elements are passed up through aligned openings in the upper and lower plies of the blanket so that the resulting hammock consists of two plies of the blanket material upon which the user may repose. 100 The soft, warm surface of the blanket material makes a very comfortable hammock, and when used in this manner provides two thicknesses of the blanket material beneath the user, effectually protecting him from cold 105 from beneath.

110 As shown in Figs. 6, 7 and 8 the complete blanket structure comprises two or more independent plies of material, one of which for example may be waterproof or water-resistant. Usually each such ply consists of a "single" blanket, the two plies 15 and 16 (Fig. 7) being united by seams along 115 their edges and preferably having the lateral bindings 17 and the end bindings 18. Reinforced openings 20 for the reception 120 of suspension elements are provided at the ends of this blanket as previously described. In place of uniting the two plies 15 and 16 along both lateral edges and at both ends, they may be united at one end and at one lateral edge only and provided with independent bindings at the opposite free edges and ends, as shown for example at 21 and 22 in Fig. 8. The employment of a pair of single 125 blankets rather than a "double" blanket facilitates the process of manufacture and may in some instances be preferred.

130 While the arrangements shown in Figs. 2 and 7 are quite desirable when additional

blankets are available for covering the user, it is possible to dispense with a separate covering blanket, while at the same time enjoying all of the advantages of a hammock. 5 Thus, as shown in Fig. 3, the blanket is doubled in the same way as in Fig. 2, and while the suspension device at the left-hand end of the hammock (as viewed in Fig. 3) is attached to both upper and lower plies of the blanket, the suspension device at the right-hand end is secured only to the lower ply of the blanket, leaving one lateral edge and the right-hand end of the upper ply free. 10 This upper ply may now be turned back, as indicated at 14, to permit the user to slip beneath it, the upper ply now serving as a blanket or coverlet to protect the user from the cold. The device shown in Fig. 8 may be used in the same way. The 15 combined hammock and blanket thus provided is found very useful by campers, who are restricted as to the amount of baggage which they may carry, since it supports the user above the ground, and provides a soft, 20 warm bed and coverlet, thus combining in one article the advantages of both hammock and blanket.

While in Fig. 3 the lower end of the upper 25 ply is shown attached to the suspension device, this is not necessary. On the other hand it is evident that if desired the free lateral edge of the blanket may be provided with suitable fasteners, such as laces, snaps, or buttons, so that when used as shown in 30 Fig. 3, these edges could be united, thus forming in effect a suspended sleeping bag. Other utilities and modifications of the structure here shown will doubtless occur to the user, but all such modifications and substitutions of equivalents are regarded as falling 35 within the scope of the invention as defined by the appended claims.

I claim:

1. A combined hammock and sleeping bag 40 comprising a blanket having spaced openings along its opposite edges, the blanket normally being folded along its median line to form upper and lower plies with the openings of the upper and lower plies disposed in super- 45 posed pairs, a supporting device for each end of the blanket, each supporting device comprising a plurality of flexible members each furnished with a loop element, each loop element passing through a pair of aligned open- 50 ings in the blanket, and a flexible securing member extending through the loops at each end of the blanket whereby normally to connect the doubled blanket at its ends to the 55 respective suspension devices to form a two- 60 ply hammock, the securing member at one end at least, being readily removable there- 65 by providing for disengagement of the upper 70 ply at will from the loops at said end while 75 still engaging them with the lower ply 80 whereby to convert the hammock into a 85 90 95 100 105 110 115 120 125 130

sleeping bag having the upper ply free from the lower ply at said end.

2. A combined hammock and sleeping bag comprising a blanket having a soft napped surface, flexible reinforce strips of textile 70 fabric extending along each edge of the blanket and along its longitudinal center line, the blanket having spaced openings along its opposite end margins and series of fastener elements along its opposite longitudinal edges, a suspension device for each end of the blanket, each suspension device comprising a plurality of flexible members each having a loop adapted to project through an opening in the end margin of the blanket, 80 readily removable flexible securing members adapted to pass through the loops at the respective ends of the blanket to unite the blanket to the corresponding suspension device, the blanket when fully extended forming a 85 single-ply hammock with the suspension loops passing each through a single ply, when doubled forming a two-ply hammock with the suspension loops each passing through aligned openings in the upper and lower 90 plies, and forming a sleeping bag when doubled and with the loops at one end passing through both the upper and lower plies, and the loops at the other end passing through the lower ply only, the fastener elements 95 serving to close the sleeping bag, thus formed, along its longitudinal edge, and when wholly released from the suspension devices being useful as an ordinary blanket.

Signed by me at Esmond, R. I., this 4th day 100 of May, 1928.

DEXTER STEVENS.
